H. H. Dyke

UNITED STATES PATENT OFFICE.

JOHANNES TH. PEDERSEN, OF FLUSHING, NEW YORK, ASSIGNOR, BY MESNE ASSIGNMENTS, TO THE MEASUREGRAPH COMPANY, A CORPORATION OF MISSOURI.

CLOTHOMETER-GAGE.

1,398,565.

Specification of Letters Patent. Patented Nov. 29, 1921.

Application filed December 9, 1919. Serial No. 343,636.

To all whom it may concern:

Be it known that I, JOHANNES T. PEDERSEN, a citizen of the United States, and a resident of Flushing, county of Queens, and 5 State of New York, have invented certain new and useful Improvements in Clothometer-Gages, of which the following is a specification.

My invention relates to apparatus for 10 measuring cloth, ribbons and the like.

My invention is particularly useful when applied to a type of measuring machine in which the fabric to be measured is pulled through a guide slot in the housing of the 15 machine, the fabric in passing through the slot operating to rotate a measuring roller whose rotation is imparted to the indicating mechanism. Such machines have usually been provided with a pivoted knife mounted 20 within or on the rear wall of the housing with respect to the direction in which the cloth is pulled; hence the rear wall of the housing constitutes the point or particular 25 plane from which the cloth is measured. In making a measurement with such a machine, it is therefore necessary to aline the forward edge of the cloth substantially with the rear wall of the housing before beginning the 30 measuring movement. In practice the operator of such a machine finds it difficult to effect the preliminary alinement referred to for the very practical reason that it is necessary for the forward edge of the cloth to project far enough beyond the rear wall of 35 the housing, to permit it to be seized by the fingers; the result is that operators tend to be careless in making this alinement and have a tendency to start the measuring 40 movement with a small portion of the cloth projecting beyond the side of the housing.

Of course, in any one measurement this portion of cloth is small, and yet the aggregate loss to the seller in measuring large 45 quantities of cloth in this way is considerable, particularly where cloth is being sold at a relatively high price per yard.

The general object of the present invention is to overcome this difficulty and to provide simple means to facilitate the accurate 50 preliminary alinement of the cloth before making the measurement; and also to mount the knife so that it will be safely guarded.

Further objects of the invention will appear hereinafter.

55 The invention consists in the novel fea-

tures, and in the general combination of parts to be particularly described hereinafter, all of which contribute to produce a simple and efficient clothometer gage. A preferred embodiment of my invention will be particularly described in the following specification, while the broad scope of my invention will be pointed out in the appended claims. 60

An embodiment of my invention is illustrated in the accompanying drawings in 65 which Figure 1 is a front view of a measuring apparatus of the "clothometer" type equipped with a measuring ledge and cutting apparatus. Fig. 2 is a side view of the ledge and cutting apparatus, Fig. 3 is a plan view 70 of the measuring ledge with the cutting knife in the down position. Fig. 4 is a perspective view of the knife guard. Fig. 5 is a horizontal section on line 5—5, Fig. 2. Fig. 6 is a perspective of the knife spring. 75 Fig. 7 is a section on the line 7—7, Fig. 2, and Fig. 8 is a detail of a roll operating handle.

Reference character 10 designates the housing of a cloth measuring or metering 80 machine. The measurement is accomplished in a well-known manner through rotation of the measuring roller 11 by the cloth 12 when pulled past it, the cloth being held in contact with the roll 11 by means of the spring-actuated presser roll 13. Roll 13 is operated by handle 14 before taking the measurement, to separate it from roll 11 to admit the cloth therebetween, and again after the 85 measurement has been taken, to release the cloth. The presser roll presses the cloth 12 up into engagement with the measuring roll 11. The measuring apparatus may be of any desired construction, and the detail construction thereof is not illustrated herein. 90

The cloth being measured, or the edge thereof, is received in and passes through a gap or slot 15 in housing 10, into which the faces of rolls 11 and 13 extend. The bottom of the slot is substantially horizontal. 95 At one side of the housing 10, preferably the rear side with respect to the direction from which the cloth is pulled, the housing 10 is provided with a laterally projecting ledge 16, the upper face whereof is substantially in 100 alinement with the bottom of slot 15 in the housing 10. Such ledge may be constructed in various ways. In the form shown it is made out of a piece of angle bar separate 105 from the housing and attached thereto by 110

screws 17 passed through the angle bar flange 18.

The outer edge 19 of ledge 16 is freely exposed and rapidly accessible; it is also at a distance from the side of the housing, and in full view of the operator. Hence it is well adapted for use as a measuring gage for positioning the end of a piece of cloth thereon in beginning the measuring operation and also for notching its edge when the desired length of material has been passed through the measuring device.

While the edge of the ledge may be used as a marking gage or may be made sharp and used for starting a tear to mark the cut-off line, I prefer to provide a knife for this purpose in line with the edge of the ledge, which can be readily actuated to cut or mark the goods measured off. The knife is preferably provided with a guard, but the handle, by which the knife can be readily operated, is exposed.

In the form shown the edge 19 of ledge 16 is cut away somewhat toward one end, producing a notch or recess 19^a (see Fig. 3) which is provided with a stationary cutting blade 20 in line with the edge 19 and adapted to coöperate with a movable blade, the two blades acting together substantially like a pair of shears. Blade 20 is secured to the vertical flange 21, of an angle clip which is secured to the underside of the ledge 16; and the blade 20 and member 21 are provided with an opening 22 to provide a bearing for the pivot or pivot bolt 23 of the pivotally mounted blade 24. At the outer end of blade 24 is the operating handle or thumb-piece 25.

Pivot 23 has a head 26, and between this head and the depending member 21 is the coil spring 27, one end of which is secured to head 26 of pivot 23, as by screw 27', and the opposite end of which is received under and held down by the downward and rearward extension 16' of ledge 16. Spring 27 serves the dual purposes of keeping the blades in close and cutting contact and holding blade 24 with its handle or thumb-piece in its raised or uppermost position. The guard 28, preferably formed as a metal stamping, surrounds blade 24 and the back 29 thereof serves as a stop to limit the upward movement of blade 24. The face plate 30 of guard 28 is provided with a slot 31 in alinement with the slot 15 in the housing 10, and the inturned portion 32 has a vertical flange 32^a that operates as an extension of the rear wall of such slot 15, with which it alines. The guard 28 is secured in place on the ledge member by screws passing through openings 33 and 34 and its top and end flanges 35 and 36.

In the operation of the device the cloth, ribbon, tape or other textile material to be measured is placed in the apparatus, roll

13 being first depressed by handle 14; after the fabric is in place the handle is operated and the presser roller released to grip the material against the measuring roll 11. The free end of the material is brought to the edge 19 of ledge 16 as the starting point, and the material is drawn to the left until the indicating mechanism (not shown) indicates that the proper length has been obtained, whereupon the blade 24 is depressed and a cut made in the material. It is then removed from the apparatus, roll 13 being depressed to permit removal, and is then cut or torn off completely across. If desired, the ledge can be extended beyond the knife and provided with a line or mark thereon in line with the knife and adapted to be used in measuring, instead of the edge 19.

It will be evident that with the provision of the ledge with its determining edge projecting laterally and freely accessible, the measuring can be accomplished with ease, speed and precision, and without waste of material.

The form illustrated is for affording a clear understanding of my invention only, and changes and modifications may be resorted to, within the scope of my claims, without departing from or sacrificing the advantages of my invention.

I claim:

1. A housing for a measuring machine, having a guide slot through which the cloth is pulled when measuring the same, in combination with a ledge adjacent the slot, and projecting from the rear side of the housing, and means carried on the ledge and removed from the side of the housing for marking the edge of the fabric.

2. A housing for a measuring machine having a guide slot for the cloth, in combination with a ledge adjacent the slot, the upper face of the ledge being substantially in alinement with the bottom of the slot, said ledge projecting from the rear side of the housing, and means carried on the ledge and removed from the side of the housing for marking the edge of the fabric.

3. A housing for a measuring machine having a slot, in combination with a ledge projecting from the rear side of the housing, a knife pivotally carried by the ledge adjacent the edge thereof remote from the side of the housing, and a guard normally receiving the knife.

4. A housing for a measuring machine having a guide slot with a substantially horizontal lower face for guiding the underside of the cloth, and a rear face for guiding the edge of the cloth when pulled through the slot, in combination with a ledge projecting from the rear side of the housing with its upper face substantially alining with the bottom of the slot, a fixed blade

carried by the ledge, a pivotally supported knife to coöperate with the fixed blade, a guard normally receiving the knife and means for normally holding the knife with-
5 in the guard.

5. A cloth measuring machine housing having a slot, in combination with a ledge projecting from the rear side of the housing, for supporting the cloth, a fixed blade
10 supported by said ledge adjacent its outer edge, a knife guard comprising two substan-

tially vertical plates disposed apart to receive a knife, a pivotally mounted knife, a pivot pin for supporting the same, and a spring disposed around the pivot pin for 15 pressing the movable knife laterally against the fixed blade and for normally holding the knife within the knife guard.

In testimony that I claim the foregoing I hereto set my hand, this 8th day of 20
November, 1919.

JOHANNES TH. PEDERSEN.
